Inventor:

UNITED STATES PATENT OFFICE.

WILLIAM G. PILKINTON, OF BUFFALO, NEW YORK.

DEVICE FOR TRANSFERRING AND DISPENSING LIQUID.

1,353,069.

Specification of Letters Patent. Patented Sept. 14, 1920.

Application filed May 10, 1919. Serial No. 296,153.

To all whom it may concern:

Be it known that I, WILLIAM G. PILKINTON, a citizen of the United States, residing at Buffalo, in the county of Erie and State of New York, have invented certain new and useful Improvements in Devices for Transferring and Dispensing Liquid, of which the following is a specification, reference being had therein to the accompanying drawing.

My invention relates to devices for transferring and dispensing liquid and is particularly useful in pharmaceutical work and for other commercial purposes such as filling fountain pens and the like.

It is my purpose to provide a device of this character through the instrumentality of which accurate quantities of a liquid can be transferred from one container to another and which will always indicate to the operator the amount that has been delivered to the receiving container.

My invention can be carried into practice in various ways, but preferably I associate it with the cork or closure of the bottle from which a given liquid is to be removed and dispensed and I will describe and illustrate the same in such adaptation although it will be understood that its association with a cork or closure is not essential in carrying the invention into practice.

With the above and other purposes in view the invention consists in the details of construction and in the arrangement and combination of parts to be hereinafter more fully described and particularly pointed out in the claims.

In describing my invention in detail reference will be had to the accompanying drawings wherein like characters of reference denote corresponding parts in the several views, and in which

Figure 1 is a vertical section of a bottle showing my invention associated with the cork thereof, the valve element of my invention being shown in open position in full line and closed position in dotted lines;

Fig. 2, a similar view showing the bottle or container inverted for the purpose of filling my improved liquid transferring and dispensing device;

Fig. 3, a vertical section of a tumbler and a portion of my device showing the manner of dispensing liquid therefrom after the lat-

ter has been removed from its original container;

Fig. 4, a bottom view of my device;

Fig. 5, a view of a bottle partly in elevation and partly in section showing a modified form of my invention;

Fig. 6, a vertical section showing my invention associated with the closure of an ink bottle, and

Fig. 7, a view partly in elevation and partly in section showing the manner of transferring ink from the bottle to a fountain pen.

Referring to the drawings, 10 indicates a bottle containing liquid 11 and closed by a cork 12 or other suitable closure. My improved liquid transferring and dispensing device is shown as comprising a tubular vial 13 preferably glass and having one end sunk in the closure 12 so that the removal of the closure will effect removal of the device. The end of the tubular vial 13 remote from the closure 12 is tapered as at 14 and is normally closed by a valve 15 having a stem 16 extending to the exterior of the vial and of considerably less diameter than the associated opening in the end of the vial so as to permit proper discharge of liquid when the valve is in open position. The stem 16 is carried laterally at 17 and then returned inwardly at 18, the free end of the portion 18 terminating in a lateral toe 19 for a purpose that will presently appear. Formed on the body of the vial 13 in any suitable manner are graduations or scales 20 through the medium of which the amount of liquid that has been dispensed can be at all times observed. For the proper operation of my device the body of the vial 13 is provided with a vent opening 21 to relieve any vacuum that would occur in dispensing liquid from the vial.

In the use of the form of my invention illustrated in Figs. 1 to 4 it will be observed that when the closure 12 is inserted in the neck of the bottle, and the bottle inverted as shown in Fig. 2, the valve 15 will, due to gravity, assume a position where the discharge end of the vial will be open, thereby allowing a portion of the liquid in the bottle or container 10 to be transferred to said vial. The bottle is then righted or brought to its normal position, as shown in Fig. 1, and when this is done the valve 15 in the discharge end of the vial will seek

its closed position under the influence of gravity so that when the closure 12 is removed the vial will carry a supply of the liquid which may thereafter be discharged as desired. To deliver any given quantity of the liquid from the vial it is only necessary to engage the toe 19 on the edge of the opening of the receptacle into which the liquid is to be delivered. By then pressing down lightly on the closure 12 the valve 15 will be lifted to open position so as to permit flow of liquid from the vial 13 as clearly shown in Fig. 3. The amount of liquid delivered from the vial can be readily determined by observing the scales 20 and when the proper amount has been dispensed it is only necessary to lift the device away from the receiving receptacle when the valve 15 will automatically close and prevent further delivery of liquid.

In the form of the invention shown in Fig. 5 I positively hold the valve 15 in closed position by means of a spring 22 and in order to assure the opening of the valve under these conditions I make the vial 13 sufficiently long with respect to the bottle in which it is used to assure the engagement of the valve stem with the bottom of the bottle to effect the lifting of the valve to open position, all as is clearly shown in Fig. 5.

In Figs. 6 and 7 the construction of my invention is the same as that illustrated in Figs. 1 to 4 except that the opening of the valve is positively effected by engagement of the valve stem with the bottom of the bottle, such a construction being preferably resorted to where the liquid is susceptible to thickening or coagulation such as commercial writing ink.

It may be noted in connection with both forms of this invention that the operator may, as desired, open the valve to its full extent so as to permit the liquid to pour in a stream from said vial, or he may by only allowing the valve to partially open, permit the liquid to discharge from the vial in the form of drops, the lateral extension 17 of the stem 16 of said valve facilitating this dropping operation.

It is to be further noted that in the event the bottle should be only partially filled

with liquid and a vial used which does not reach to the bottom of said bottle, then the filling of the vial is accomplished by inverting the bottle, as heretofore described, to the position shown in Fig. 2, where the valve 15 will be opened, and permitting the liquid, which in this instance does not reach to the discharge end of the vial, to pass into the vial through the air vent 21, displacing the air in such vial and allowing the air to pass through the discharge end of said vial, the valve 15 being in open position as above set forth. 65

I claim:—

1. In a device of the character described, a closure for bottles and like containers, a vial secured to and depending from said closure, said vial having a discharge mouth 70 at its depending end and a vent in the side thereof adjacent its connection with said closure, and a valve for normally closing said mouth.

2. In a device of the character described, 75 a solid closure or stopper for bottles and like containers, a vial secured to and depending from said closure, said vial having a discharge mouth at its depending end and a vent in the side thereof adjacent its connection with said closure, a valve within the vial normally closing said mouth, and means on the valve extending exteriorly of the vial for operating said valve. 80

3. In combination with a bottle or other 85 container, a closure for said container, a vial depending from said closure and immovable with respect thereto, said vial having a discharge mouth, a valve within the vial normally closing said mouth when the vial is 90 removed from its container, and means on the valve extending exteriorly of the vial for operating said valve, said means engaging a part of the container for holding the valve in open position when the closure 95 is in place with the vial positioned within said container.

In testimony whereof I affix my signature in presence of two witnesses:

WILLIAM G. PILKINTON.
